UNITED STATES PATENT OFFICE.

HENRY M. PIERSON, OF NEW YORK, N. Y.

APPARATUS FOR MANUFACTURING GAS.

No. 882,907.

Specification of Letters Patent. Patented March 24, 1908.

Application filed April 22, 1907. Serial No. 369,466.

To all whom it may concern:

Be it known that I, HENRY M. PIERSON, a citizen of the United States, residing at the borough of Brooklyn, in the county of Kings, 5 city and State of New York, have invented an Improvement in Apparatus for Manufacturing Gas, of which the following is a specification.

My invention relates to a new and novel 10 form of apparatus for the manufacture of gas in which according to the process employed, a fuel or producer gas, a non-luminous water gas and a luminous or illuminating gas may be manufactured; the parts which are necessarily 15 connected therewith for the full performance of the methods of manufacturing being old in the art and not necessarily requiring illustration herein.

In the apparatus employed by me I provide 20 a retort vertically disposed and which constitutes a substantial prolongation of a generator, the same being suitably constructed and supported, and I provide means for supplying to this retort progressive or continuous 25 charges of bituminous coal which are periodically converted into coke to be added as fuel to the body of fuel in the generator.

The generator, *per se*, is of usual construction; the retort rising therefrom and the lower 30 end of the retort extending into the generator, and the retort being a substantial communicating prolongation or stack of the generator. One or more throats pass off from the upper end of the retort with branches 35 and suitable valves and carry away the gas produced, all of which is hereinafter more particularly described.

In the drawing, Figure 1 is a vertical section representing the apparatus of my improvement and Fig. 2 is an elevation in smaller size showing two of these devices coupled together.

The generator which rests upon a suitable foundation is formed as usual with a metal shell *a* and a lining *a*¹ of refractory material which is provided with suitable grate-bars *b* of any desired or well-known character in this art. A pipe *b*¹ extending through the generator beneath the grate-bars brings into the generator a supply of air under pressure and a pipe *c* conveys into the generator steam. At the upper end of the generator I prefer to form stoke-holes *d* *d*¹ with suitable

caps which may be made use of if desired for the introduction of bars in mixing up or disturbing the fuel forming the fire. 55

I provide support beams *g* and eye-beams *f* resting thereon and at right angles thereto, both of which are located at the upper part of the generator, and a flange in the upper shell 60 of the generator preferably passes over the eye-beams *f* which assist in supporting the upper part of the generator shell.

The tubular tapering shells *e* *e*¹ are super-imposed; the lower shell *e* resting upon a support ring 5 above the eye-beams *f* and a support ring 6 coming between the shells *e* 65 *e*¹. These parts are suitably bolted together and thus firmly secured. At the upper end of the shell *e*¹ is a support ring 7 and resting thereon is a drum *i*¹, to which is connected the lower end of a hopper *i*, the upper end of the hopper *i* being by preference secured to a suitable beam 8. Within this drum *i*¹ there is a revoluble feeder consisting of a shaft and 70 blades *k* which are suitably driven.

Within the shells *e* *e*¹ are retort chambers *h* *h*¹ *h*² of tapering form made of refractory material and having flanges 2 3 and 4. These retort chambers are super-imposed on 80 one another and their flanges rest upon and are supported by the rings 5 6 and 7. These retort chambers may be and preferably are cemented together at their joints and the lower and larger open end of the retort 85 chamber *h* projects approximately half way into the generator. I prefer to use asbestos as a lining between the shells and retort chambers.

The retort chambers receive bituminous 90 coal fed to them from the hopper *i* by the revoluble feeder *k* and said bituminous coal is adapted to extend below the lower end of the retort chamber *h* and to rest upon the fuel in the generator and as the same is converted into fuel coke by extracting the chemical substances therefrom, the said bituminous coal falls periodically or progressively upon the bed of fuel in the generator for replenishing the same. 95

I provide a throat *m* extending off from one side of the retort near the upper end and an air pipe *m*¹ entering the same. I also provide extending off from the opposite side of the retort at the upper end a throat *n* with a 100 branch *n*¹ and a valve *n*² and I provide pipes 105

^{o¹} passing through the shell of the retort and through the retort chambers for conveying within the retort liquid hydro-carbon.

As shown in Fig. 2 of the drawing, I have 5 illustrated two of these devices coupled together and from which the throats *m* extend off in the opposite direction, in which the pipes *n* are coupled together and the branches *n¹* may be coupled together. This 10 duplication of the apparatus is for the economical and alternate operation of the same in a continuous method of producing gas.

I have not shown in the drawing but it is 15 common in this art to employ a washer and scrubber and also a gasometer or holder, and I prefer to extend the coupled pipes *n* to these devices. It is also common in this art to provide a carbureter and to one or more of these devices I connect or extend the 20 throats *m*; said carbureters being provided with smoke-stacks and valves and pipes which extend out to a gasometer. The essential features of my invention are however shown in the drawing.

25 In the devices of my invention as hereinbefore described, it is quite apparent that there is no portion open to external air, and no portion that need be opened to external air except in rare instances, consequently 30 the closed apparatus is particularly advantageous for the manufacture of gas, especially in maintaining the heat and not cooling down while charging the apparatus with coal and removing the ashes, and even this 35 latter condition is measurably assisted by the employment of an advantageous form of grate-bar which however is no necessary part of my invention.

In the operation of the device of my improvement, the generator is filled with fuel 40 and the retort with bituminous coal fed from the hopper *i*; the generator is fired and blown up to incandescence and producer gas is made as is usual in this art. The producer 45 gas passes up through the bituminous coal in the superimposed retorts, the coal in which,—with the fuel in the generator—form a continuous body of fuel material. The producer gas tends to distil the coal and form fuel 50 coke. When producer gas alone is made, it passes off by the pipes *n* and *n¹* upon the lifting of the valve *n²*. After making producer gas the air is shut off and steam is admitted 55 into the incandescent fuel and is converted into its constituents,—forming water gas. This water gas is enriched by passing through the bituminous coal and coke and by taking up the vapors of hydro-carbon introduced by the pipes *o¹*. The water gas 60 then passes by the straight line pipe *n* over the valve *n²*, the same being shut, and passes through its water seal to a holder. The producer gas may be carried by the pipe *m* and be burned by air admitted by the pipe *m¹* so

as to heat up a checker-brick fixing chamber 65 through which water gas alternately made with the producer gas may be passed if desired; Fig. 2 showing the apparatus generally adapted for carrying out the alternate process.

70 I claim as my invention:

1. In an apparatus for the production of gas, the combination with a generator and means for introducing air and steam alternately into the same, of a downwardly flaring retort vertically disposed and connected with and forming a substantial prolongation or extension of the generator, and in which the bodies of fuel are continuous, means for feeding bituminous coal to this retort and 80 means at the upper end of the retort for conveying away both the blast and all other gases.

2. In an apparatus for the production of gas, the combination with a generator and 85 means for introducing air and steam alternately into the same, of a downwardly flaring retort vertically disposed and connected with and forming a substantial prolongation or extension of the generator and in which the bodies of fuel are continuous, means for feeding bituminous coal to this retort, means for conveying away the blast and all other 90 gases from the upper end of the retort and means for introducing air into the means for 95 conveying away the gases.

3. In an apparatus for the production of gas, the combination with a generator and means for introducing air and steam alternately into the same, of a downwardly flaring retort vertically disposed and connected with and forming a substantial prolongation or extension of the generator, and in which the bodies of fuel are continuous, means for feeding bituminous coal to this 105 retort, means for conveying away the blast and all other gases from the upper end of the retort, means for introducing air into the means for conveying away the gases and means for introducing liquid hydro-carbon 110 into the retort.

4. In an apparatus for manufacturing gas, the combination with a generator and means for introducing air and steam alternately into the generator, of a vertically and centrally disposed retort forming a prolongation or extension of the said generator and opening into the same, said retort being continuously tapering, largest at the lower end within the generator and smallest at the upper 120 end, a hopper for receiving and a feeder for discharging bituminous coal into the retort and means for conveying away from the upper end of said retort both the blast and all other gases produced.

5. In an apparatus for making gas, the combination with a generator of suitable character and pipes for introducing air and

steam alternately into the lower portion of said generator, of a retort formed of a plurality of tapering and super-imposed flanged sections rising from said generator, forming a substantial prolongation thereof, the largest lower end of said retort opening into the generator, a shell surrounding said retort sections, supports from said shell to the flanges of said sections and suitable means beneath for supporting the shells and the retort so that the weight thereof is carried independently of the generator.

6. In an apparatus for the production of gas, the combination with a generator and means for introducing air and steam alternately into the same beneath the grate bars,

of a retort vertically disposed, connected with and upon the generator, forming a rising prolongation or extension of the generator and of tapering form throughout, with its larger lower end within and forming a substantial unitary chamber with the generator, means at the higher and smaller end of the retort for feeding bituminous coal to the retort and other means similarly located for conveying away both the blast and all other gases.

Signed by me this 5th day of April 1907.
H. M. PIERSON.
